UNITED STATES PATENT OFFICE.

ACHILLE KNAFEN, OF BRUSSELS, BELGIUM.

BUILDING BLOCK.

Application filed September 2, 1921. Serial No. 498,072.

(GRANTED UNDER THE PROVISIONS OF THE ACT OF MARCH 3, 1921, 41 STAT. L., 1313.)

To all whom it may concern:

Be it known that I, ACHILLE KNAFEN, a subject of the King of the Belgians, residing at Brussels, in the Kingdom of Belgium, have invented certain new and useful Improvements in Building Blocks (for which I have filed applications in Belgium December 12, 1919, Patent No. 283,778; in France December 17, 1919, Patent No. 10 507,445; and in Germany April 23, 1920), of which the following is a specification.

This invention relates to an agglomerate block of cement mortar, hydraulic lime, bitumen, etc., mixed with sand, brickbats, 15 ashes or other suitable substances. This block is chiefly intended to enable hygienic buildings to be quickly erected free from condensation and drawbacks due to the diathermal properties of the cement compound 20 pounds.

Numerous constructions of porous or non-porous agglomerates, with or without a single or double air space, have already been suggested for remedying the scarcity 25 of the usual building materials and for enabling dwelling houses to be quickly built. All the houses built of cement agglomerates endowed with different porosities, are affected by the diathermal properties peculiar to agglomerates of that kind; the 30 wall having to be reduced to their minimum thickness in view of the high price of the materials are attacked by moisture through capillarity when they are too porous, and 35 become impregnated with water of condensation and with rain driven thereon by the wind. It follows that the said walls become greater and greater conductors, and consequently greater condensers; they cool 40 the interior, the occupants of which are unable to keep warm.

It has been already attempted to remedy the drawbacks in question by rendering the walls thus constructed, impermeable in their mass; this method does not however give the results anticipated, as the impermeabilisation renders them conductors on account of their low degree of specific heat which frequently places them at the dew 50 point relatively to the temperature and to the degree of saturation of the inner air of the premises occupied. Several years of practical experience have proved that such constructions are unhealthy, and at the

end of a relatively short period become uninhabitable for human beings. 55

The present invention obviates all these drawbacks, whilst at the same time making it possible to benefit by the facility of manufacture and by the various advantages 60 of the agglomerates from the building point of view. To that end, the invention is based on the observation that the provision of an inert air space in porous compounds, makes it possible to prevent conduction with condensation on the walls, vertical penetration of moisture by capillarity and horizontal introduction of wind driven rain, so that by adding to houses built with porous compounds provided 65 with an inert air space, a suitable automatic ventilation, it is possible to obtain an ideal house from the point of view of health and comfort. 70

It has been scientifically proved that an 75 air space comprised between two walls, is not really inert unless it is less than 30-45 mm. thick. The inventor has found moreover by numerous experiments that such inert air spaces, in order to be efficacious, must 80 be arranged so to say progressively from the outside towards the interior so as to keep the maximum degree of caloric inertia at the inner face of the wall, which is alone in contact with the air in the inhabited 85 rooms.

In accordance with the said principles, a block according to the invention is characterized by the fact that whilst being made with a binding medium such as cement 90 mortar, hydraulic lime, bitumen, etc., mixed in proportions determined by the nature of each individual wall, with quantities variable according to the circumstances, of brick bats, pussolan, or pumice stone, etc., 95 it is provided in its thickness with an air space of a proportional and progressive thickness (but not exceeding 45 mm.) between the outer face and the inner face of the block. 100

The accompanying drawing shows by way of example constructions according to the invention.

Fig. 1 is a plan of a normal block;

Fig. 2 is a similar view of a corner block. 105

The block *a* made as already stated from cement mortar, hydraulic lime, etc., mixed with brick bats, ashes, etc., is provided in

its thickness with hollows or recesses b producing an inert air space of a thickness progressing between the outer face c and the inner face d of the wall of the house.

- 5 In the example illustrated, these inert air spaces are assumed to show a progressive thickness comprised between 30 and 45 mm.; moreover the said air spaces are arranged so as to be staggered relatively to each other 10 from one row to another, so as to exercise efficaciously their action throughout the whole thickness of the block and in any transverse plane of the same.

The blocks could be made in different 15 thickness, from 90 mm. inner partitions up to 500 mm. and more for the outer walls. The height depends on the dimension of the apparatus used for the manufacture. The angles or corners of buildings are 20 formed by means of blocks constructed as shown in Figure 2, so as to produce corresponding air spaces in the portions adjacent to the two sides of the outer angle.

Having regard to the inertia of the air 25 spaces it is not necessary, in erecting buildings, to open or close vertical conduits producing the air spaces. The movement of the air molecules is prevented in an efficacious manner by the special dimensions 30 of the air spaces which are insulated from each other, and the conduits could be eventually closed by the mortar utilized for making the vertical horizontal joints, without the effect desired being modified.

35 The length of the conduits forming the

air spaces, could eventually vary according to the position of said air spaces in the thickness of the block, the reduction of the diathermal properties of the block varying in proportion to their depth.

If it is desired to use blocks or panels of this kind with inert air spaces, not only on account of their special properties above referred to, but also as sound and heat insulators, or heat the centre row or one or more of the end rows of the recesses, could be packed with slag wool or mineral wool, asbestos waste, crushed coal, pounded glass, or any other material which is a non-conductor of heat or sound.

50 What I claim is:

A building block formed with a number of inert air spaces arranged in a plurality of rows with the air spaces of one row in staggered relation with the air spaces of 55 adjacent rows, the said air spaces being of progressive thickness from the outer to the inner face of the block, whereby said air spaces exert their maximum effect in that part adjacent to the inner face of the block 60 and whereby the density of the block is greater in that part adjacent to the outer face of the block and gradually decreases toward the inner face of such block.

In testimony whereof I have affixed my 65 signature in presence of two witnesses.

ACHILLE KNAPEN.
